DIAMOND DRILL FEED CONTROL

Henry S. Hoffar, Vancouver, British Columbia, Canada, assignor to International Multifeed Drills, Ltd., Vancouver, British Columbia, Canada, a corporation of British Columbia

Application July 12, 1939, Serial No. 284,067

6 Claims. (Cl. 255—46)

My invention relates to devices for drilling rock. The invention is best illustrated in conjunction with a diamond drill, but certain principles thereof, as will appear hereafter, may be applied also to percussion rock drills. The invention is concerned primarily with the feed arrangements for such drills, having in mind the conditions under which they are intended to operate.

It is considered preferable, in the operation of certain diamond drills, to employ high speed rotation, and rather light pressure to advance the drill rod, since thereby the life of the diamond points can be materially increased. However, it is desirable to advance the drill as rapidly as it is capable, without undue wear, of cutting through the rock, but the rate of feed is a variable quantity, and depends upon the resistance encountered, which in turn depends upon the rock formation with which the point is engaged, and, as such factors vary from time to time, a rate of advance which would be permissible under some conditions might be unduly rapid and destructive of the drill point if persisted in under other conditions. It has not been considered practicable to provide an automatic feed, either hydraulic, pneumatic or mechanical, which would be wholly self-adjusting to the different conditions encountered from time to time, to accomplish advance of the drill at whatever rate is best suited to the conditions momentarily encountered, and changing from moment to moment, yet I have discovered how this may be done, and it is an object of the present invention to provide feed arrangements and controls to accomplish the above end.

It is also desirable to provide means, when employing a pressure fluid as the primary means to accomplish advance, to accomplish manual feed when desirable, and to provide further means whereby, should the drill point pass into a fissure or rock chamber, it will not advance suddenly under the applied pressure across the fissure and strike the opposite wall, for such impact is extremely destructive of the diamond points. Such occurrences are infrequent, yet it is desirable to provide means, if that can be done without undue complications, whereby, in a drill employing a pressure fluid as the primary advancing means, restraint can be imposed upon the advance to prevent such unrestrained plunging forward when the resistance is wholly removed.

It is also desirable to provide feed means or feed controlling means, especially for use where

the advance is primarily accomplished under the influence of a pressure fluid, whereby the permitted maximum rate of advance may be varied at will to suit different operating conditions, yet without increasing the pressure at the drill point, and it is an object of the present invention to provide control means adjustable to this end.

Diamond drills, particularly such as are portable, that is, capable of being transported from point to point and supported in operative position upon a mine bar, have heretofore included a pressure cylinder and a piston movable therein to accomplish advance of the drill rod, the drill rod being in effect connected in prolongation of the piston or extending through it, in such manner that in order to accomplish feed of the drill rod, and the connection of successive sections, it was necessary to have available as clear space approximately twice the over-all length of the drill or its feed cylinder. When operating in cramped quarters, as in a mine drift or tunnel, working space is limited, and it was necessary under such conditions to shorten the length of the drill itself to about half the available space, thereby necessitating frequent stoppages for back feed of the piston, and for connection of additional lengths to the drill rod. Not only did this consume time, but it required additional couplings. It is desirable, therefore, to provide feed mechanism for such drills which will give a length of advance equal to substantially the entire clear space available, to the end that stoppages may be less frequent and sections may be longer, and it is an object of the present invention to provide feed mechanism for such uses having the capabilities and advantages indicated, and which is also suited to the other necessary conditions which it encounters in use.

It is a further object to provide feed mechanism of the sort indicated, incorporating a cylinder and a slide externally thereof, connected to the piston within by a cable bent over sheaves at opposite ends of the cylinder, which slide supports a rotative motor in the case of a diamond drill, or a rotative or reciprocative percussion device in the case of a rock drill, which device, in either instance, is so mounted that it may be swung aside out of the line of the drill rod, so that, for instance in a diamond drill, additional sections may be coupled on, or the drill rod may be pulled out.

Still a further object is the improvement in

diamond drills in matters of detail, as will appear hereafter.

My invention comprises the novel parts, and the novel combination and arrangement thereof, as shown in the accompanying drawings, described in this specification, and as will be more particularly defined by the claims which terminate the same.

In the accompanying drawings I have shown my invention embodied in a form which is at 10 present preferred by me.

Figure 1 is a perspective view, with parts broken away, illustrating a diamond drill, the feed mechanism of which is in operative position with relation to the mine bar and to the drill rod, but in which the rotative motor and coupling to the drill rod have been swung aside for access to the drill rod.

Figure 2 is a longitudinal section through such feed mechanism, substantially on the line 2—2 of Figure 3, the parts being rearranged somewhat from the showing in Figure 1 for convenience of illustration.

Figure 3 is a part elevation and part section, taken on the line 3—3 of Figure 2, and Figure 4 25 is a transverse section substantially on the line 4—4 of Figure 3.

A pressure fluid is still employed as the primary forcing or advancing means, and hence within a cylinder 1, closed by the ends 10 and 11, is slidable a packed piston 2. The cylinder heads 10 and 11 are held upon the ends of the cylinder 1 to close it, preferably by tension means extending through the cylinder and the piston, as shown at 12 and 13. In effect these are tension rods, and the member 12 is an actual rod anchored at the two ends. The member 13 is a hollow rod, however, having an aperture 14 at one end, within the cylinder, the rod extending through the head 11 at this end and provided with a cap 15 to close this end, so that fluid entering at the opposite end, adjacent the head 10, will be admitted into the cylinder through the aperture 14.

The cylinder is made of approximately the length of the clear space, and while certain devices, applied externally, reduce the length of the cylinder somewhat, it is of a length considerably more than half the expected feed distance, and affords an extent of advance considerably more than half the clear distance. To this end, instead of a rigid piston rod projecting from the piston 2, a flexible cable 22 is anchored at 20 in the piston, extends through suitable packing glands 21 at the cylinder heads, and thence over sheaves 23 supported externally upon each cylinder head. Being thus reversed in direction, externally of the cylinder, the cable 22 extends to a slide 3 mounted upon and guided for movement lengthwise of the cylinder 1, to which slide 25 the cable 22 is anchored, as indicated at 24. A suitable guard 25 may surround the sheaves 23.

By such an expedient the piston 2 may move substantially the full length of the cylinder 1, being stopped in this instance by the glands 21 or by suitable stops, at about this point, or by stops engaging the slide 3, which is connected to the drill rod D. The slide 3 may have a length of travel equal to the travel of the piston within the cylinder, and yet the cylinder may be made of a length almost equal to the full extent of clear space in the drift.

The cylinder 1 is normally mounted for swiveling upon a mine bar M by means of a swivel head 17 received in a similarly shaped socket

carried by the mine bar, the head 17 being permanently secured to the exterior of the cylinder, as by welding. By reason of the projection of the head 17 the slide 3 may not be completely circular, but is saddle shaped, as is best seen in Figure 4. To prevent its rotation around the cylinder a key 31, received in a groove in the exterior of the cylinder, is received likewise in a corresponding groove in the slide 3.

Carried by the slide 3, but preferably indirectly through interposed means, which will be described, is a coupling 5 which is adapted to fit within the end of the drill D. Since the coupling 5 is mounted upon the slide 3 it partakes of the latter's lengthwise movement. The coupling 5, especially in the case of a diamond drill, is likewise rotative about the axis of the drill rod, rotation being accomplished in such a case by a rotative motor 4. The form of this motor is largely immaterial. As shown herein it is a rotary motor intended for operation by compressed air, and its form and arrangement is of importance to the remainder of the invention only in that it is somewhat unbalanced dynamically, and thereby tends to produce vibration. Being directly coupled to the drill rod, it is intended for rotation at the rate of rotation best suited for operation of the drill.

This motor 4, being in alignment with the drill during normal drilling, is preferably so mounted that it may be swung aside when it is desired to engage the drill rod to withdraw it, or when it is desired to couple on a further length of drill rod. Accordingly the motor 4 is mounted pivotally or swingably upon the slide 3 at 43, and is normally held to the slide, against swinging, by a swingably mounted bolt 42 receivable within a fork 34 of the slide 3. In Figure 4 the motor is shown in operative position, and in Figure 1 it is shown swung aside. Hose connections for supply of pressure fluid or for water supply have been omitted from the drawings, but would be flexible to permit such swinging. In Figure 1 there is shown the control valve 41 for regulating the supply of the pressure fluid for rotating the motor 4. The motor's shaft 40 is in alignment with the drill rod D and one end of its shaft carries the coupling 5 when in the position of parts shown in Figure 4.

It is convenient to note at this point that a pressure fluid, whether air or water or oil, is supplied to the interior of the cylinder 1, at one side or the other of the piston 2, through the head 10. The fluid is supplied by a connection at 60 past a metering valve 61, and past a four-way valve 6, controlled by the handle 62, by means of which the pressure fluid may enter directly through the head 10, by way of the connection at 63, or by way of a connection 64 to the end of the hollow rod 13, previously mentioned, and by means of which the pressure fluid is admitted to the distant face of the piston. A pressure limiting or reducing valve may also be employed at this point, if desired or required.

The feed mechanism thus far described is operative without more to effect feed, under the influence of the pressure fluid acting upon the piston 2, and to effect drilling under the influence of rotation effected by rotation of the motor 4. However, there are times when it is desired to employ hand feed, or to control manually the rate or extent of feed, and I have therefore provided a manual feed screw, and in so doing I have discovered that such a feed screw, when employed in conjunction with the pressure fluid

advance, when there is a vibratory element present, will serve also to control the rate of advance automatically, without the interposition of any manual means or control, precisely in accordance with the extent of resistance encountered.

The feed screw 7 is journaled by combined rotative and thrust bearings 70 in the opposite heads of the cylinder. The saddle or slide 3 is provided with a trough through which the feed screw 7 passes, but with which it has no threaded engagement. This trough merely serves to position it, and to back it up when the feed screw is engaged by a half nut 71. This half nut 71 is guided in a frame 37 upon the slide 3, and its position is controlled by a screw 72 connected through a swivel with the nut 71, and provided with a handle 73 whereby the screw 72 may be rotated. By backing off the nut 71 the feed screw 7 may be left wholly free of the slide 3, and consequently of the piston 2, and under such conditions the feed is accomplished wholly by means of and under control of the pressure fluid. If the opposite ends of the cylinder are vented to remove artificial resistance of the fluid to advance, feed may be accomplished wholly under manual control through the feed screw 7, and by means of an operating or turning arm 75 securable upon an end of the screw 7.

However, when operating under the influence of the pressure fluid, I have discovered that if the nut 71 be left in engagement with the screw 7, control of the advance may be accomplished with little effort, and manually, by turning the handle 75, and indeed may be accomplished wholly automatically, the handle turning to permit advance, but only at a rate which is a function of the length of the arm and the mass of the handle 75, which constitutes an unbalanced weight affecting the periodicity or amplitude of the vibrations generated by the motor 4, the vibration also being affected somewhat by the resistance of the rock encountered by the drill point.

It is not entirely clear to me just why this action occurs. It has been discovered by me in practice, and I have discovered how the same may be controlled and regulated, but the operation is substantially the same no matter in what direction the drill point is operating, whether down, up, or laterally. The action is always to feed the drill point forwardly by automatic rotation of the feed screw 7 in the proper direction, but only at a rate which is consistent with the resistance encountered by the drill point. If the resistance increases, the speed of rotation of the drill point and of the motor 4 is reduced, thereby reducing the rate or periodicity of vibration of the entire assembly, and in consequence decreasing the rate of rotation of the feed screw 7, and thereby the rate of advance. The rate of advance is thus automatically compensated and made to correspond to the resistance encountered, and a diamond drill, thus equipped, in operation, operates by repeated surges as the drill speeds up and then meets increasing resistance and slows down, and then speeds up again. The variation in speed is not appreciable, but sufficient to be noticed.

In attempting to explain this action it appears to me that the pressure of the pressure fluid against the piston reacts through the cable 22, the slide 3, and the nut 71 upon the screw 7, tending to create friction to hold the screw against rotation, though, by pressure, tending to slide the nut along the incline of the screw 75

thread, and thus to induce rotation of the screw. However, the whole assembly is set into vibration by the rotation of the motor 4 as it is affected by the dynamically unbalanced handle

5 75. This effects momentary release of the nut from the feed screw, because there is necessarily working clearance between the two, and since the fluid pressure on piston 2 presses the nut along the screw, it tends to rotate, its thread 10 sliding down the thread of the nut 71. Rotation in the proper direction is assured because the follow-up of the piston pressure prevents reverse rotation, and tends to slide the nut down the screw thread, inducing the 15 screw's rotation in the proper direction. The extent to which it may feed is thus dependent upon the periodicity and amplitude of the vibration, since change in its periodicity affects the number of releases and reengagements between the nut 20 and screw, and the amplitude affects the severity of the shock between them, upon each engagement. I have found that variation of the length of the arm of handle 75 upon the screw influences the rate of advance by its effect on the vibration, with a given screw pitch. Consequently in order that the rate of advance may be controllable, the handle 75 is slidably received in the head 76 secured upon the squared end 77 of the feed screw 7. The handle is held in any adjusted position, transversely of the axis of the screw, by such means as the set screw 78. By adjusting the handle 75 outwardly the rate of feed is increased, and vice versa.

35 Whatever may be the true explanation, the device has been found to operate thus in practice, and there is provided by such means an extremely desirable and efficient regulation of the rate of advance by adjustment of the length of the handle arm, and automatically within the range corresponding to the handle setting in accordance with momentary changes in resistance encountered by the drill rod, to the end that the drill may continue to rotate at maximum speed and rate of advance, and yet be 40 automatically protected from too great advancing pressure, or from too high speed consonant with the pressure actually applied.

45 What I claim as my invention is:

1. A diamond drill or the like comprising a coupling for connection to the drill rod, a slide carrying said coupling, a closed cylinder disposed parallel to the drill rod and constituting a parallel guide for said slide, a piston slidably 50 lengthwise within the cylinder, means to supply a pressure fluid within the cylinder to accomplish such movement of the piston, a sheave at each end of the cylinder, a cable, suitably packed at the cylinder heads, anchored to the piston and to the slide, and extending over the sheaves, to transmit lengthwise movement of the piston to the slide, coupling, and drill rod, a screw and nut 55 extending parallel to the cylinder, and operatively connecting the cylinder and the slide, and means effecting vibration of the assembly during fluid feed, thereby to regulate the feed rate automatically through the screw and nut.

2. A diamond drill or the like comprising a slide and a coupling carried thereby for connection to the drill rod, a cylinder and a piston 60 slidably lengthwise thereof, and operatively connected to the slide to advance the coupling and the drill rod, means to supply a pressure fluid within the cylinder to effect such advance, a screw journaled upon and extending parallel

to the cylinder, a nut engaged with the screw and carried by the slide, an arm projecting radially from the screw, and means effecting vibration of the assembly during fluid feed, thereby to regulate the feed rate along the screw, in accordance with the character of the vibration governed by the effective length of said arm.

3. A diamond drill or the like comprising a coupling for connection to the drill rod, a closed cylinder and a piston slidable lengthwise thereof, a slide carried by and guided upon the cylinder for lengthwise movement, a rotative motor carried by the slide and operatively connected to the coupling, an operative connection between the piston and the slide, including a cable anchored to each and guided at the ends of the cylinder, means to supply a pressure fluid within the cylinder to effect advance of the piston, and reverse feed of the slide and coupling, a feed screw parallel to and journaled upon the cylinder, an arm projecting laterally therefrom, and a nut carried by the slide, and engageable with the screw, vibration of the assembly upon rotation of the motor permitting advance of the slide and coupling at a rate dependent upon the resistance encountered and the degree of lateral projection of said arm from the screw.

4. The combination of claim 3, including means operable at will to retract the nut from engagement with the screw.

5. A diamond drill comprising a cylinder and a piston movable lengthwise therein, heads clos-

ing the opposite ends of the cylinder, a slide guided upon the cylinder for movement lengthwise thereof, means, including a cable anchored to each of the piston and slide, and running over guides at each end of the cylinder, for moving the slide equally and oppositely by movement of the piston, a coupling for connection to the drill rod, carried by said slide, means extending through the piston and cylinder, and holding the heads upon the cylinder, said latter means including a hollow rod connected at one end to a pressure fluid source, and opening within the cylinder beyond the piston, for supply of pressure fluid for advance of the piston and slide, and valve means to control the supply of pressure fluid through said hollow rod.

6. In a rock drill, the combination of a support, a drilling and drill-engaging means, a pressure fluid feed means to advance the drill-engaging means, a feed screw and nut operatively connected between the support and the drill-engaging means, and subject to pressure of the fluid feed means, vibratory means, a mass carried by the screw eccentrically thereof, and means to adjust the degree of eccentricity of the mass, thereby to regulate the vibration of said vibratory means which in turn influences the rate of relative rotation of said feed screw and nut, and consequently regulating the rate of advance of said drill-engaging means governed by such relative feed screw and nut rotation.

HENRY S. HOFFAR.
